UNITED STATES PATENT OFFICE.

WILLIAM S. FOSTER, OF DALLAS, WISCONSIN.

ROAD-PLANER.

1,336,215.

Specification of Letters Patent.

Patented Apr. 6, 1920.

Application filed March 10, 1919. Serial No. 281,767.

To all whom it may concern:

Be it known that I, WILLIAM S. FOSTER, a citizen of the United States, residing at Dallas, in the county of Barron and State 5 of Wisconsin, have invented new and useful Improvements in Road-Planers, of which the following is a specification.

The primary object of this invention is to provide an improved road-finishing device, 10 which is particularly adapted to plane off transverse ridges in roads rendering the surface of the road plane.

It is an especial object of my invention to provide an improved planing tool for 15 such a machine; and to provide improved means for mounting the teeth used in the machine.

With these and other objects in view, my invention is disclosed in the accompanying 20 drawings, in which—

Figure 1 is a top plan of my invention; Fig. 2 is a side elevation of same, partly in section; and Fig 3 is a section on line 3—3 of Fig. 1.

25 Referring to the drawings, I provide a long runner 1, and short runners 2 and 3. Runners 1 and 2 are provided with downwardly turned ends to cut a path for the runners. Runners 2 and 3 are connected by 30 a suitable U-shaped or V-shaped brace 4, such as shown in Fig. 2. I provide a planing tool 5 extending diagonally from runner 1 to runner 3, to cut-out portion 10 of which its angular portion 17 is attached or 35 engages, being secured to the runner by a suitable bracket 18. Planing tool 5 is provided with cutting blade 6, of steel sharpened and turned slightly to the front to shave off the high places and send the dirt 40 to the side and center of the road, where it will pass under the inclined planing tool, thus crowning and shaping a fine grade. I provide suitable braces or cross-ties 7 and 8, between which are mounted a series of teeth 45 9, secured by the bolts 10, as illustrated. I further provide suitable cross pieces or stays 11 to brace the runners. At the rear of the machine I provide planks 12, a seat 14, and steering or manipulating handles 15, by 50 means of which the operator may assist in guiding the device when turning the machine around. The runners 1 and 2 are provided with projecting ends 13 to cut a groove in the road for the runners and to keep the 55 machine from sliding sidewise.

Suitable draft mechanism 19 is attached

to the forward ends of the runners to which horses may be hitched to propel the device when in use; but it is within the contemplation of my invention to operate same by any 60 suitable motive power.

In operation the ends 13 of the runners cut grooves for the runners while the device is being drawn ahead and prevent the plane from sliding sidewise. The harrow 65 teeth, which are adjustable to the desired depth by means of the bolts 10, serve to break up the ridges in the road so that the planing tool will cut the ground smoothly, and the planing tool being mounted in inclined position relative to the plane on which 70 runners 1 and 3 travel, planes the earth and guides same toward the center of the road, thus shaping a fine grade in an efficient manner. The planing tool extends to some 75 distance beyond runner 3, as shown, and is elevated somewhat above the bottom edge of that runner, preferably as illustrated in Fig. 2. The runners 2 and 3 are connected by a suitable brace which serves to keep 80 them in proper alignment.

It is within the contemplation of my invention to suitably modify any of the details of construction herein disclosed, the apparatus illustrated being that which I 85 now consider to represent the best embodiment of my invention.

What I claim is:

1. In a road planer, the combination of a long runner, alined spaced short runners 90 parallel to the long runner, an upwardly arched brace connecting the short runners, an inclined relatively short and rigidly mounted planing tool, having its inner end attached to the long runner, and having its 95 outer end projecting substantially beyond the short runners, said planing tool extending from substantially the bottom edge of the long runner to a slightly elevated position relative to the short runners, whereby 100 to send the dirt toward the side and center of the road where it will pass under the inclined planing tool and shape a fine grade.

2. In a road planer, the combination of a plurality of parallel runners, a relatively 105 short and rigidly mounted planing tool attached at one end to one of the runners and extending substantially beyond the other runner, said planing tool being positioned in upwardly inclined relation to the runners 110 from the point of attachment to the first mentioned runner, and a harrow element

carried by the road planer in advance of the planing tool, said harrow element having means for vertical adjustment of the harrows, for the purposes described.

- 5 3. In a road planer, the combination of a plurality of longitudinally alined and spaced runners a third parallel runner; an upwardly inclined relatively short diagonally mounted planing tool rigidly attached 10 to the runners and extending beyond the runners of the machine on one side only; cross braces connecting the runners with each other, an arched brace connecting the spaced longitudinally alined runners over 15 the planing portion of the machine, a plurality of harrow supporting braces arranged in advance of the planing tool, and harrows adjustably mounted therein.

4. In a road planer, the combination of a plurality of parallel runners, a relatively 20 short rigid planing tool, a spaced runner alined with one of the afore-mentioned runners and to which the planing tool is affixed in diagonal and elevated relation to the parallel runner on the opposite side of the 25 machine and past which it extends, cross braces connecting the runners with each other, the aforesaid planing tool being removable, and harrow teeth arranged in staggered relation in cross braces in advance 30 of the planing tool, and forwardly projecting teeth at the forward end of the parallel runners to shape the grade, substantially as described.

WILLIAM S. FOSTER.
